SPINNING TOP

Edward S. Savage, Rochester, N. Y.

Application May 27, 1938, Serial No. 210,406

16 Claims.

(Cl. 46—65)

My invention relates to spinning tops and a primary object of the invention is to provide what may be termed an "aquatic" top—that is to say, a top having floating means which will permit it to be spun on water or other liquid for a considerable length of time, while the liquid does not offer any resistance to the spinning of the top.

Another object of the invention is to provide what might be aptly termed an "amphibian" top—that is to say, a top which will spin while floating on water and will also spin on land or other supporting surface, regardless of whether the surface is smooth or rough.

Another object of this invention is to provide an improved form of bounding top.

Another object of the invention is to provide an improved form of bounding top with detachable bounding means which may be easily detached from the top and easily attached thereto.

Another object of the invention is to provide an "amphibian" top with floating means which also constitutes a bounding means.

Another object of the invention is to provide a top having a separate spinner head operating in a manner similar to a well known type of top and spinner head, but eliminating the use of the usual stem extending above the top to receive and guide said spinner head.

Another object of the invention is to provide an improved top spinning means which may be carried by the top while spinning without interfering with or offering any resistance to the spinning of the top.

Another object of the invention is to provide a bounding top in which the bounding member is pivotally connected to the top permitting the top to spin while supported on the stationary bounding member.

Another object of the invention is to provide a bounding member in the form of a ball which may be hollow and charged with an air or other gas pressure in excess of atmospheric pressure.

In the drawings

Figure 1 is a vertical sectional view of the preferred embodiment of the invention with the spinning head in position to be rotated for spinning the top.

Figure 2 is a perspective view in side elevation of the top shown in Fig. 1 representing the top as spinning on water without the spinner head.

Figure 3 is a side elevation of a spring actuated spinner head designed for spinning the top shown in Figs. 1 and 2.

Figure 4 is a perspective view of the top shown in Fig. 1 in which the top is represented as spin-

ning on water with its spinning axis inclined at an acute angle in relation to the surface of the water.

Figure 5 is a perspective view of the top shown in Fig. 1 illustrating the gyroscopic action of the top as it spins horizontally with its flotation element resting on a stationary support.

Figure 6 is a view in side elevation and partly in section of a modification of the invention adapted to be spun by a string.

Figure 7 is a vertical, sectional view of another modification of the invention in which a spring element for spinning the top is carried centrally within the spinning member.

Figure 8 is a vertical sectional view of another modification of the invention in which a spring element for spinning the top is carried within the flotation member.

Figure 9 is a view in side elevation, with most parts in central section, of a modification of this invention as applied to a conventional gyroscopic top.

Figure 10 is a perspective view of a flat circular spring stop or locking means employed in the three modifications of the invention shown in Figs. 7, 8 and 9.

Similar reference numerals throughout the several views refer to similar parts.

Referring first to the embodiment of the invention shown in Fig. 1 and illustrated perspective in Figs. 2 to 5; the principal elements of the embodiment of my invention here shown are the spinner head A, the rotating member or body B, the vertical spindle C and the combination float and bounding member D. In this construction the body A comprises the oppositely formed body sections or shells 10 and 11 preferably made of sheet metal and joined together by the peripheral seam 12. The upper shell 10 is provided with an integral raised central portion 13 having a generally flat surface, which latter is provided with diametrically opposite orifices 14 and circumferentially arranged indentations 15. These orifices and indentations are provided to cooperate with interengaging clutch and locking means carried by the spinner head A. A flanged tip member 16 fits into a center hole in the shell 10 with the flange 17 bearing against the shell, the lower end 18 of the tip member 16 fits into a hole in the center of the flanged disc 19 and is secured therein by being swaged or riveted over as shown, thus securing the disc 19 in fixed position with its upwardly formed peripheral flange 20 in contact with the under surface of the shell 10. This disc 19 serves to prevent a flow of air into 55

the top body through perforations in the raised portion 18, which flow of air would reduce or destroy the humming sound of the top. It also supports the ends of the downwardly sloping tongues of sheet metal forming the bottoms of the indentations 15.

5 The tip member 16 is formed with an axial hole 21 extending upwardly from the bottom thereof with reduced diameter at its upper end to provide a supporting thrust bearing for the top body B to rotate about the stationary spindle C. The spindle C terminates at its upper end in the small pivot bearing 22 and is freely journaled in the bearing hole 21. A lower bearing for the body 15 B is provided by the flanged hole 23 in the center of the shell 11. The usual "humming" holes 24 near the periphery of the lower shell 11 and two similar holes located diametrically opposite thereto (not shown in the drawings) cause the 20 top to emit a humming sound while spinning. A collar 25, fixed to the spindle C close to but not normally contacting the shell 11, serves to prevent withdrawal of the spindle C from the top body B. The lower end of the spindle C is 25 provided with a knob 26 and fits into a corresponding socket in the hollow rubber ball D which functions both as a floating element and a bounding element. This elastic socket connection of the spindle C to the ball D provides a 30 simple means for removably attaching the ball D to the spindle C, the ball being easily removed from the spindle by pulling it therefrom or replaced by forcing it thereon. With the ball D removed, the top may be spun, as an ordinary 35 top, on the rounded tip 26, or the top may be spun in inverted position on the tip 16.

Referring to the construction here shown pertaining to the top spinning means; the improved spinner head A, shown in Figs. 1 and 3, is in 40 most respects the same as the well known "Gibbs" spinner head which has long been used to spin smaller sizes of hollow sheet metal tops. Therefore it is not considered necessary to describe in detail the parts of this construction here shown 45 which are old and well known.

My spinner head comprises the spool shaped wood body 27, the helical actuating spring 28, the locking pin 29, the helical spring 30 for holding the locking pin in lowermost position and the 50 sheet metal cap 31 seamed onto the top of the wood body 27. The novel feature of this construction resides in the provision of a centrally located tube 32 which fits loosely within the spring 28, and extends upwardly thru a free 55 fitting center hole in the cap 31. The upper end of the tube or driving stem 32 is closed in rounded form and its lower end is cut to form two diametrically opposite claw shaped teeth 33 which extend below the lower end of the body 27 and 60 form in effect a clutch end to enter and engage with the two orifices 14 which are located close to and on opposite sides of the tip member 16. It is obvious that, instead of the two clutch teeth 33 here shown, three or more equally spaced 65 clutch teeth may be provided on the end of the tube 32 and a corresponding number of orifices 14 provided in the top to engage the clutch teeth. The upper end of the spinner spring 28 is fastened to the wood body by the tack 34 as is 70 customary, while the lower end of the spring, instead of having the usual downward hook, is bent to form a horizontal inwardly extending hook 35 which is hooked into a hole in the tube 32 as shown.

75 In use the spinner head A is placed centrally

against the top, the lower end of the tube 32 being placed over the tip member 16 which serves as a guide to centrally locate the spinner head in the position shown in Fig. 1. The head A is then rotated in a clockwise direction. The teeth 33 enter and hook into the orifices 14 and further turning of the head winds the spring 28 while the locking pin 29 falls successively into the indentations 15 to prevent backward movement of the head and to retain the spring 28 in energized condition. It should be noted that while the head A is being turned and after the spring has been brought to proper tension, the tube 13 is held in axial alignment with the axis of the top because the turning force of the spring transmitted to the tube 32 and angularly undercut leading edges of the teeth 33 tends to hold the tube tightly against the flat surface of the top thus eliminating any tendency to cock the tube and spinning head over at an angle in relation to the axis of 20 the top.

Heretofore tops employing the above mentioned "Gibbs" type of spinning head have been provided with an axial stem (usually a metal tube) extending from the lower top member upwardly 25 through and to a considerable height above the upper top member and rounded at its upper end, such stem being necessary to receive and guide the spinning head and to provide means for depressing and detaching the top from the spinning 30 head by pushing downwardly on the upper end. In my construction no upwardly extending stem is employed on the top, thus effecting a considerable saving in weight of the top which is particularly desirable in a floating top and also contributing to the attractive appearance of the top. Elimination of the stem also permits the use of the tip member 16 on the point of which the top may be caused to spin in an inverted position. After winding the spinning head A the top may 40 be spun by preferably holding it vertically and pressing down on the rounded end of the tube 32, which operation withdraws the locking pin 29 from engagement with one of the indentations 15 and permits the spring 28 to rotate the tube 45 32 and so spin the top through the clutch connection of the teeth 33 in the orifices 14. As the beveled teeth constitute an overrunning clutch, the top will release itself and fall away from the spinner head B. If desired the spinning operation 50 may be performed by one hand while the ball D is held in the other hand.

Referring to Fig. 2 in which the wavy lines W represent the surface of water; when the top is spun it may be held by the ball float D and placed 55 vertically on water where it will continue to spin in a vertical position, as here shown, for a considerable length of time, while the ball D may rotate at a slow speed due to slight friction of the bearings against the supporting spindle C. If the ball D touches the side of the water container, the rotation of the ball will be stopped momentarily.

As the spinning speed decreases the top will 65 begin to tilt with its spinning axis at a gradually increasing angle from the vertical while the axis of the top slowly revolves with precessional movement, as indicated by the dotted line in Fig. 4, until the top finally topples over. If the top is 70 spun and first placed in an inclined position on the water it will continue to spin in an inclined position while its axis revolves slowly with precessional movement and the inclination of the axis from the vertical will gradually increase 75

until the spinning speed becomes too slow to support the top.

Obviously it is possible to employ, instead of the round ball float here shown, a float having some stability or tendency of its own to remain upright on water, the stability being due to a flatter shape of wider area or due to a weighted bottom. Such a float could be made to hold the top upright until and after it had stopped spinning. There would, however, be no surprising or mysterious effect in the performance of such a top. The fact that an unstable float and attached top, which will not stand up on water when not spinning, will stand up on water and perform as this top does while spinning, tends to create much surprise and interest in its performance. The same is true in reference to the other modifications of the invention shown in the drawings.

In Fig. 5 the top is represented performing as a gyroscopic top, spinning in a horizontal position with its spherical float member D supported on the mouth of the bottle E. As indicated by the dotted circle (in perspective), the spinning top revolves with precessional movement, slowly about a vertical axis coincident with the center of the bottle, while spinning in the horizontal position. Any suitable support with slightly concave top of sufficient width will serve to demonstrate this gyroscopic performance of the top. In making this demonstration, it is preferable to first place the spinning top nearly vertical in a slightly tilted position on the support, then the top will gyrate with gradually increasing angle from the vertical until it finally is spinning with its axis sloping downwardly and will fall from the support only when the top body contacts the support. As already mentioned, the hollow rubber ball shaped float D is designed to function also as a bounding member and so employed adds greatly to the play value of the top. This ball is preferably charged with air or other gas under a pressure greater than atmospheric pressure in order to increase the height of the rebound.

While various forms of bounding tops have been made and patented, the improved and novel features of my invention produce better and more interesting bounding actions and permit a play performance with this top impossible with existing forms of bounding tops. The chief advantages obtained in my construction are due to the fact that the bounding member is not rigidly attached to the top but is rotatably attached thereto permitting the top body to revolve independently of the bounding member and to the fact that my construction preferably employs a comparatively large hollow resilient rubber chamber or ball with internal gas or air pressure producing an excessively high rebound.

The interest in former bounding tops resides in the fact that they may be spun and dropped to a hard surface such as a floor when they will rebound several times while the top spins. With such tops the height of each successive rebound is less than half the previous rebound, the result being that the high bounding is very brief and only the first two or three rebounds are of sufficient height to create interest in the performance. It is, therefore, necessary to again spin the top to again enjoy the brief bounding effect.

The chief advantage in my bounding top resides in the fact that the top may be caused to bound higher than other bounding tops and that the bounding may be caused to repeat many times during one spinning of the top. To accomplish

this result the person or player manipulating the top spins the top and then holds it spinning upright on the palm of the hand. He then tosses it up to a considerable height in the air resulting in a high rebound. The player then quickly thrusts the open palm of his hand under the top as it reaches the upper limit of its rebound and allows it to fall thereon where it will continue spinning in an upright position. He again tosses the top upward and repeats the performance as long as the top continues to spin. If the player wishes he may catch the top on the second or later rebound or he may wait until the top ceases bounding, then pick it up by means of the ball D and again toss it upward to repeat the bounding action, which performance may be repeated as long as the top continues to spin.

Another method of playing with the top and one which may be employed in the playing of a game is for two or more players to catch the top in turns on the rebound or the top may be tossed directly from one player to the other to be caught on the palm of the hand of the receiving player while the top continues to spin in an erect position. Other types of bounding tops cannot be caused to perform in the various ways described above because they will not bound high enough, and to catch such spinning top with its pointed tip on the palm of the hand would be obviously unpleasant or harmful and if so caught the friction of the hand against the top, even momentarily, would soon cause the top to stop spinning.

Figure 6 shows another modification of my invention in which the rotor or spinning body member B1 is made of solid material such as wood or suitable composition in the form of a wheel with a rim 36 of circular cross section, a web 37, an upper hub 38 and a lower hub 39, both hubs being provided with beaded peripheries at their ends. An axial hole 40 extends vertically through the hubs to provide clearance for the spindle C1. A flanged metal tip member 41 is secured to the end of the upper hub 38 by being crimped over the beaded end of the hub as shown at 42. This tip member carries the central rounded tip 43 and is formed with an axial hole 44 which provides the supporting thrust bearing for the body B1 to rotate about the stationary spindle C1, the upper end of the spindle C1 being turned to form a pivot to fit freely in the bearing hole 44. The sheet metal cap 45 is crimped onto the beaded hub at 46 and is pierced centrally to provide the lower bearing for the spindle at 47. The spindle C1 passes through the float member D1 and is held in position by the collar 49 fixed to the shaft C1 and the flanged lower end 49 of the spindle. A collar 50, fixed on the spindle C1, slightly above the bearing 46, serves to retain the body member B1 against removal from the spindle C1. The spherical float member D1 is preferably made of some very light weight material such as white cedar, cork or balsa wood. Since the type of float here shown is not of itself elastic a bounding element is provided by the coned spiral spring 50 which is fastened to the flattened lower surface of the float by means of the staples 51 or any other suitable means. A rounded button 52 is preferably secured to the lower end of the spring 50 to provide a suitable bearing surface for catching the top on the palm of the hand on the rebound.

In use this top is spun by the old string method, the string being wound around the upper hub 38 and pulled away quickly by one hand while the float member D1 is held in the other hand. This

top will perform on water or gyroscopically the same as the top shown in Figs. 1 to 5 and described in the foregoing. The coiled spring bounding means does not, however, produce as high a rebound as the hollow rubber ball with internal air pressure already described. Obviously this top may also be fitted with the rubber ball type of float and bounding member. In Fig. 6 the top is shown spinning upright on a surface. It will also spin in inverted position on the tip 43.

Figure 7 illustrates another modification of my invention differing primarily from the embodiments of the invention already described in that the spinning means is wholly incorporated in the top. In this construction the rotating member or top body B2 is formed of the two sheet metal shells 60 and 61 seamed together at 62. A tip member 63 is swedged into a center hole in the shell 60 at 64, the rounded point 65 serving as a spinning tip when the top is spun in an inverted position. An axial hole 66 serves as the supporting thrust bearing for rotation of the body B2 on the spindle C2. A tubular extension 67 of the tip member 63 extends axially downward therefrom and furnishes a supporting means for the sleeve 68 which is tightly fitted thereon. The sleeve 68 is provided with an inner annular flange 69 encircling but not contacting the spindle C2. The spindle C2 carries the fixed collar 70 close to but not normally contacting the flange 69 which serves to retain the body member B2 against removal from the spindle C2. The vertical axially positioned tubular shell 71 fits freely at its upper end over the sleeve 68 which furnishes a bearing therefor for rotational and longitudinal movement thereon. The lower end of the tube 71 fits freely in the flanged bearing hole 71a formed centrally in the lower shell 61. A circular sheet metal disc 72 is fastened to the end of the tube 71 by means of tongues 73 which enter slots in the disc and are bent inwardly as shown. The disc 72 is pierced at its center to form a bearing 74 to rotate about the spindle C2. The disc also carries at its periphery two or more equally spaced depending teeth 75 which are preferably beveled similar to the teeth 33 shown in Fig. 3. The actuating spring 76 loosely encircles the tube 71. Its upper end carries a hook 77 which is hooked into a sheared indentation 78 of the shell 60. The lower end of the spring is provided with an inwardly bent hook which enters a hole in the tube 71 at 79. The shell 61 is formed at the bottom with a generally flat circular surface 80, which surface has indentations 81, preferably three or four in number, formed similarly to the indentations 15 shown in Fig. 2 and serve a like purpose. The lower end of the spindle C2 is inserted into a tube or socket in the rubber float 60 and bounding member D2, the grooves 82 near the end of the spindle serving to increase the grip of the rubber socket on the spindle. This connecting means permits detaching the float member from the spindle by pulling it therefrom. In this construction the spindle cannot carry an integral enlargement such as the knob 26 of Fig. 7 because it is necessary when assembling the parts that some parts be put onto the spindle from the lower end.

The curved circular sheet metal shell 83 is provided with a flat upper portion 84 and a hole 85 in the center thereof fits freely on the spindle C2. A sheet metal saucer shaped shell 86 is fastened inside of the shell 83 by means of the 75 seamed or crimped joint 87. A hole 88 in the

center of the shell 86 fits freely on the spindle C2, the two shells 83 and 86 forming a unit which may be rotated on the spindle C2 and may also be moved longitudinally thereon.

A flat circular spring 89, shown also in perspective in Fig. 10, is riveted at one end to be normally held against the under surface of the flat upper portion 84 of the shell 83, the rivet hole being shown at 90, and the other end of the spring is bent upward to form a vertical prong as shown at 91. The vertical prong passes up through a free fitting slot pierced in the shell 83. The elasticity of the spring 89 is such that the vertical prong 91 may be depressed by moderate pressure and will return to the upper position shown when the pressure is removed. Orifices 92 in the flat surface 84 correspond in number to the teeth 75 and are positioned to engage with the latter when the shell 83 is moved upward and rotated, the orifices 92 and teeth 75 forming a driving clutch when shell 83 is turned in one direction which will disengage when the spring 76 is deenergized and the body B2 continues to spin. A friction sleeve 93, made of some resilient material such as cork or rubber, fits only sufficiently tight on the spindle to provide frictional resistance to the longitudinal movement of the shell 83 on spindle C2.

In this way the shells 83 and 86 with the spring 89 and prong 91 form a spring winding element which may be moved upward to engage the clutch teeth 75 with the orifices 92 in which position the shell 83 may be rotated to wind the spring 76, the spring prong 91 snapping successively into the indentations 81 and acting as a locking pin to prevent reverse movement of the shell 83, the prong 91 serving the same purpose as the locking pin 29 of Fig. 1. When the spring 76 is sufficiently tensioned the top may be spun by pulling the shell 83 downward thus releasing the prong 91 from engagement with one of the indentations 81 and permitting the spring 76 to unwind and thereby rotate the body B2 while the teeth 75 are still locked in engagement with the orifices 92. It is to be noted that in pulling the spinner shell 83 downward to release the prong 91, the clutch teeth 75 do not disengage but pull the tube 71 downward with the spinner shell 83. When the spring is completely deenergized the beveled teeth 75 disengage from the orifices 92 and the tube 71 moves up to its normal position and the body B2 continues to spin freely, there being no further contact with the spinning means. The friction of the sleeve 93 on the spindle C2 serves to normally retain the spinning shell in its lowermost position as shown in the drawings. In performance this modification of the invention is similar to the forms shown in Figs. 1 to 5 and described in the foregoing.

The modification of the invention shown in Fig. 8 also carries the entire spinning means, the actuating spring being located in the float. It may be noted that, as far as the spinning means is concerned, this construction is very similar to that of Fig. 1 in principle of operation, except that in this construction, the spinning means is not removable from the top. This similarity is more readily observed by viewing Fig. 8 in an inverted position. It will therefore not be necessary to elaborate at length on the functions of the different parts comprising this modification. The rotating member or top body B3 comprises two sheet metal shells 100 and 101 seamed together at 102. A tip member 103 provides a tip on which the top may be spun in an inverted

position and also provides the supporting thrust bearing 104. A flat surface 105, forming the bottom of the shell 101, is provided with the orifices 106 and indentations 107 similar to the orifices 14 and indentations 15 of Figs. 1 and 2. The spindle C3 terminates in the pivot bearing p at its upper end and carries the collar 108 which serves to retain the body member B3 against removal from the spindle C3. In this construction the float and bounding member D3 comprises the rigid upper member 109 preferably made of light weight wood or cork and the lower elastic bounding member 110 preferably made of rubber formed substantially hemispherical in shape with an inside annular bead 111 at its upper periphery which fits into a corresponding groove in the rigid upper member 109, the two members 109 and 110 forming the substantially spherical float member D3. The upper portion of the member 109 is formed with a flat, circular raised portion 112 with a groove 113 encircling its base. An axial hole 114 extends from the surface 112 to near the bottom of the member 109, to provide a chamber to receive the actuating spring 115. A sheet metal cap member 116 with straight tubular periphery 117 fits on the raised portion 112, its lower edge being crimped into the groove 113 as shown. The cap member 116 has a center hole 118 which provides a free fitting bearing for the tube member 119. A flat circular spring 89, shown in perspective in Fig. 10, is riveted at its flat end 90 to the under surface of the shell 116, with its vertical end or prong 91 extending upward thru a free fitting hole in the cap 116. This spring member 89 and prong 91 is a duplicate of the part 89 described in connection with Fig. 7 and serves a like purpose, the spring 91 acting as a locking pin to engage with the indentations 107.

40 A clutch disc 120 with beveled upwardly extending teeth 121, two or more in number and equally spaced about the periphery of the disc, are adapted to interlock with a like number of similarly spaced orifices 106. The clutch disc 120 is fastened to the upper end of the tube 119 by tongue and slot means and a center hole in the disc 120 provides a free fitting bearing for the spindle C3. The upper end of the actuating spring 115 is hooked to the cap 116 at 122 and the lower end of the spring is hooked into a hole in the tube 119 at 123. The lower end of the tube is partially closed forming a free fitting bearing on the spindle C3 at 124. A hole 125, bushed with rubber or other suitable material, furnishes a friction guide bearing for the spindle C3, permitting the spindle C3 to be moved longitudinally within limits and hold the spindle and top body 3 normally in their uppermost position as shown. A head 126 on the lower end of the spindle limits its upward movement. A rubber post 127 with a cupped upper end is formed integral with the rubber shell 110 and serves to increase the elasticity of the bonding member and also serves as a pushing means for pushing the spindle C3 upward.

65 In use the spring 115 is wound by holding the spinning member B3 in one hand in any convenient position, forcing the float member D3 toward the spinning member and rotating the member D3 until the spring is sufficiently tensioned. In the winding of this top the parts function exactly as corresponding parts in the spinner head A and spinning member B of Fig. 1. After the spring 115 is wound to proper tension, 70 the top is spun by pushing inwardly at the bot-

tom of the bounding member at 128, thereby causing the rubber post 127 to force the spindle C3 and body member D3 upward, disengaging the locking prong 91 from the retaining indentation 107 and permitting the spring to rotate the member B3. In this construction the float member D3 is not designed to be removable but the bounding member 110 may be easily pried away from the rigid member 109 if desired. It is apparent that the top may be used as a simple spinning top to spin in inverted position on the tip 103, the member 109 functioning as an attached spinner head. This top will perform in all respects similar to the embodiments of the invention described in the foregoing, but it is not as efficient on the rebound as are the embodiments employing a pressure charged hollow rubber ball as shown in Figs. 1, 7 and 9.

10 In Fig. 9 I show a modification of the invention as applied to a conventional type of gyroscopic top fitted with a combined float and bounding means and an improved spinning means carried by the top. The rotating member or fly wheel D4 is fixed to its rotary spindle C4, the spindle terminating in the small pivot bearings 150 and 151. The usual gyroscope frame is employed comprising the main ring 152 and lighter guard ring 153 at right angles thereto and shown in section welded to the ring 152 at the contact point 154. This gyroscope frame differs from the conventional type in having an upwardly extending stem 155 comprising an upper extension of the lower stem 156. The upper end of this stem 155 is drilled to provide the lower bearing of the spindle C4 at 151. This stem 155 also provides a bearing for a cylindrical spinner shell 157 which is designed for rotational and longitudinal movement thereon. The float and bounding member D4, which is removably fitted to the stem 156, is the same as the member D of Fig. 1. 40 A sheet metal cylindrical or cupped shaped shell 158 has a substantially flat bottom 159 with a central hole 160 fitted over the spindle C4, the shell being fastened at its upper end to the fly wheel by means of tongues 161 which project thru holes in the fly wheel web and are bent inwardly against the upper surface thereof. The bottom 159 is provided with the orifices 162 and indentations 163, preferably four in number, which function as do the orifices 14 and indentations 15 of Figs. 1 and 2.

45 The actuating spring 164, here employed, is the flat spiral clock spring type and is carried within the cylindrical cupped shaped metal shell 157 which is recessed and pierced at its center 165 to receive the elastic bushing 166, which bushing provides a frictional bearing on the stem 155 for rotation and longitudinal movement of the shell 157 thereon. A sheet metal embossed cover plate 167 provides a closure for the shell 157, the upper edge of which is seamed over at 168 to retain the plate 167 in fixed position. The outer end of the spring 164 is pierced and hooked onto a tongue 169 which has been sheared and bent inwardly from the peripheral wall of the shell 157.

55 The inner end of the spring 164 is bent to form an inwardly extending hook which hooks into a slot at 170 in the tubular member 171. This tubular member 171 is carried axially on the stem 155 and is flanged inwardly at its lower end to form a central bearing fitting freely on the stem 155. 70 The upper end of the tubular member 171 is fastened by tongue and slot means to a disc 172 with center hole fitting freely on the stem 155 which disc carries the equally spaced beveled teeth 173.

which teeth are adapted to interlock with the orifices 162. The flat circular spring 89, shown in perspective in Fig. 10, is riveted at the end 90 to the under surface of the cover plate 167, the upwardly projecting prong 91 passing thru a free fitting hole in the plate. It is apparent that the parts comprising the spinning means here described function the same as corresponding parts already described in connection with Figs. 1 and 8.

To spin this top the fly wheel B4 is grasped in one hand while with the other hand the spinner shell 157 is first moved upward to engage the clutch teeth 173 with the orifices 162. The shell is then rotated in the proper direction to energize the spring 164 while the locking prong 91 snaps into the indentations 163 and prevents reverse movement of the spinner shell. When the spring is sufficiently tensioned, the top is spun by pulling the spinner shell downward with one hand while holding the top in the other hand by means of the frame rings 152 and 153 or the float D4.

When the shell 157 is pulled down releasing the locking prong from engagement with one of the indentations 163, the spring 164 will rotate the fly wheel D4 thru the clutch connection of teeth 171 with orifices 162 and, when the spring 164 is completely deenergized continued rotation of the fly wheel D4 causes the clutch prongs 171 to disengage from the orifices 162. It is to be noted that when the shell 157 is pulled downward to disengage the prong 91 from an indentation 163, the teeth 171 remain in engagement with the orifices 162, causing a slight axial distortion 35 of the spring 164, its outer turns being pulled below the more central turns, the spring assuming a cone form with its center uppermost. Clearance is provided between the upper side of the spring 164 and the under surface of the cover plate 167 to provide space for this coning effect. When the clutch members disengage the tubular member 170 and attached spring 164 drop down to their normal position, permitting the fly wheel B4 to spin freely on the pivot bearings 150 and 151 without contacting any portion of the spinning means. The friction bushing 166 will normally retain the spinner shell 157 in its lowermost position. Obviously the spinning means here described may be designed to use a helical actuating spring, similar to those shown in Figs. 1, 7 and 8, instead of the flat spiral spring 164. If such a helical spring were used the stem 155 and sleeve 171 would be longer than here shown and the spindle C4 and shell 158 proportionately shorter. The spinner shell 157 would be formed to house the actuating parts and would be provided with a convenient hand hold for rotation about the stem 155.

It will be seen that I have provided in this embodiment of my invention, in addition to the new and novel features of a bounding and floating means, an improved spinning means for gyroscopic tops which eliminates the slow and tiresome string spinning method heretofore employed.

It will be apparent that, instead of the hollow rubber ball floating and bounding member shown in Figs. 1, 7, and 9 it is possible to use sponge rubber balls having a water proof surface. The hollow rubber ball is to be preferred however because of its lighter weight and better bounding qualities.

It is to be desired in any and all of the embodiments of my invention here shown, that the floating member be made as small as possible with sufficient buoyancy to carry the rotating mem-

ber above the surface of the water while the top is spinning. Therefore, to reduce the load to be carried by the float I prefer to make all metal parts, except the rotating member, the actuating spring and the spindle, of light weight metal such as duralumin or other equally light composition metal.

While I have here shown several specific applications of my invention, it will be obvious that changes and modifications may be made in the structures disclosed without departing from the spirit of the invention defined in the following claims.

I claim:

1. In combination, a spinning top, a supporting float therefor comparable in size to that of the top adapted to float on water and support said top above the surface of the water while spinning on said float, and guide means to retain said top while spinning in substantially central position on said float.

2. In a spinning top, a rotary body member, a base member, and means rotatably connecting said members to each other to permit said rotary body member to spin on said base member, said base member constituting floating means having sufficient buoyancy while floating on water to sustain said body member above the surface of the water while said body member is spinning on said base member.

3. A top according to claim 2, in which said base member has a maximum dimension in a horizontal direction, when floating upright in water, which is not materially greater than the maximum horizontal dimension of said body member.

4. A top according to claim 2 in which said base member has insufficient flotation stability to sustain said body member in upright position above the surface of the water when said body member is not spinning.

5. A top according to claim 2 in which the base member is generally rounded in form.

6. A top according to claim 2 in which the base member includes resilient bounding means.

7. A top according to claim 2 in which the base member comprises mainly rubber and constitutes resilient bounding means.

8. In a spinning top, a rotary body member adapted to be spun as a top and to remain spinning by its momentum for a substantial time after it is spun, a base member, and means rotatably connecting said members to each other to permit said body member to spin on said base member when said base member is stationary, said base member including resilient means permitting it to function as a bounding means.

9. A top according to claim 8 in which the base member comprises a substantially spherical rubber ball.

10. A top according to claim 8 in which the base member comprises a hollow rubber chamber charged with gas pressure in excess of atmospheric pressure.

11. A top according to claim 8 in which the means rotatably connecting said body member and base member comprises a spindle carried by one of said members and extends into the other member, said spindle being provided with a pivotal thrust bearing point at the free end thereof to coact with a thrust bearing carried by said other member and to pivotally sustain the weight of the rotary body member thereon.

12. In a spinning top, a rotary body member and bounding means carried thereby, said bound-

ing means including an airtight chamber which is charged with an internal gas pressure in excess of atmospheric pressure and having an elastic wall constantly tensioned by said internal pressure, which is activated when the top is bounded and which tends to increase the resiliency of the bounding means.

5 13. In a spinning top, a rotary body member adapted to be spun as a top and to remain spinning by its momentum for a substantial time after it is spun, and bounding means carried by said rotary body member, said bounding means comprising a rubber ball.

10 14. In a spinning top, a rotary body member and bounding means carried thereby, said bounding means comprising a hollow rubber ball

15 charged with gas pressure in excess of atmospheric pressure.

15 15. A spinning top including a rotatable spinning body adapted to be spun as a top and to remain spinning by its momentum for a substantial time after it is spun, and resilient bounding means readily attachable to and detachable from said body.

10 16. A spinning top including a rotatable spinning body adapted to be spun as a top and to remain spinning by its momentum for a substantial time after it is spun, and resilient bounding means rotatably attached to said spinning body and means for readily attaching said bounding means to and detaching from said spinning body. 15

EDWARD S. SAVAGE.
